UNITED STATES PATENT OFFICE.

ELMER R. CORWIN, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,173,772.

Specification of Letters Patent. Patented Feb. 29, 1916.

Application filed April 5, 1913. Serial No. 759,018.

To all whom it may concern:

Be it known that I, ELMER R. CORWIN, citizen of the United States, residing at Chicago, in the county of Cook and State

5 of Illinois, have invented a certain new and useful Improvement in Telephony, of which the following is a full, clear, concise, and exact description, reference being had to the accompanying drawings, forming a part of

10 this specification.

My invention relates to telephone exchange systems and has for one of its objects the provision of devices for interchangeably connecting idle calling line ex-

15 tensions with calling lines, such devices continuing in operation until they have effected connection between idle calling line extensions and calling lines.

My invention has for another of its ob-
20 jects the provision of means for reducing the number of motor devices in operation at one time, there being means for bringing an idle motor device into operation when a previously operating motor device

25 has been brought to rest after having per-
formed its function of extending the calling line, and this feature of the invention is broadly claimed irrespective of the manner and means whereby the motor devices
30 effect changes in or addition to the tele-
phone lines at the exchange and while the motor devices preferably do not cause the bodily travel of contacts the invention, in all of its characteristics, is not to be thus
35 limited.

In the preferred embodiment of my in-
vention the link connectors are equipped
with the motor devices that are then pre-
ferably individual thereto and by means of
40 this feature of my invention the telephone
lines may be stripped clear of line magnets
and relays. In this embodiment of the in-
vention the lines of the system are divided
into groups, say of one hundred lines per
45 group, and enough link connectors are as-
signed to such group to equal the maximum
traffic to be borne, ten link connectors
50 per group.

The invention, as shown in the embodi-
55 ment herein disclosed, is employed in con-
nection with a so-called semi-automatic sys-
tem in which the link connectors are auto-
matically connected with calling lines and
are connected with called lines by operator
55 controlled means such as terminal plugs

provided for the link connectors and spring jacks supplied to the telephone lines. The invention is, however, not to be restricted to such a system.

There are other features of my invention 60 and the various features of the invention will be further explained by reference to the accompanying drawing showing the preferred embodiment thereof and in which—

Figure 1 diagrammatically illustrates 65 telephone lines extending from substations to an exchange, all equipped in accordance with the invention; and Fig. 2 is a view illustrating a motor device.

The equipment at stations 120 and 190 70 is illustrated as including a telephone switch hook 1 having a normal contact for completing a telephone line bridge including a call bell 2 and an alternate contact for completing a telephone line bridge that 75 includes a telephone receiver 3 and a telephone transmitter 4, this latter bridge being closed when the switch hook is free of the telephone receiver and the bell bridge being closed when the switch hook supports 80 the receiver. The signal bells are prefer-
ably of high resistance, say five thousand ohms, the system of my present invention, ac-
cording to its present embodiment, enabling me to dispense with the condensers in the bell 85 bridges. The telephone lines are provided with terminals 5, 6 at the exchange, there being ten pairs of such terminals per line, as there are ten motor devices for each group of one hundred lines in the example chosen for 90 illustration. When the lines are to be adapted for connection with calling plugs they are also provided with spring jacks 7 95 multiplied in the various sections of the switchboard. The line terminals 5 and 6 are provided each with a complementary contact, similar contacts of the lines of a group being in multiple connection, such connec-
tion being understood, though there are but two lines illustrated in the drawing. Simi- 100 larly positioned contacts in each group are multiplied. Each motor device is shown as including a motor magnet 8 and a ratchet wheel 9 operated thereby. Each ratehet wheel is in actuating relation to an 105 arm 10. This arm carries a steel roller 11 adapted to ride over the contact springs 5 and in riding over such springs to depress the same to bring them into engagement with their complementary contacts at which 110

times the contact springs 6 are also brought into engagement with their complemental contacts owing to the mechanical couplings which intervene between the free ends of 5 the springs 5 and 6. The roller 11 of each motor rides over the contact springs 5 of all of the lines of the group of one hundred lines to which the motor pertains.

When a call is initiated the high resistance bell bridge between the sides of the 10 calling line is replaced by the low resistance telephone bridge so that the calling line is adapted to the transmission of current in sufficient volume to operate the equipment 15 to be described that will stop the operation of the motor, which has depressed the contacts 5 and 6 of the calling line, so as to maintain contacts 5 and 6 in connection with their complemental contacts. When the 20 contacts 5 and 6 are thus maintained in connection with their complemental contacts another and previously idle motor device is set into operation so as to enable it to maintain the contacts 5, 6 of another calling 25 line in engagement with their complemental contacts whereupon another and previously idle motor device is brought into service.

Any suitable means may be employed for 30 the motor device, that shown including the motor magnet 8 included in a circuit that contains a circuit interrupter 12 for intermittently energizing said motor magnet to cause it to operate the ratchet wheel 9 which 35 is provided with one hundred teeth, one tooth per line, each operation of the motor magnet removing the roller 11 from engagement with one contact spring into engagement with the next. The circuit for the 40 motor magnet includes the interrupter 12, said motor magnet, the normal contact of the armature switch of relay 13, the left hand armature switch of energized relay 14, and the grounded battery or source of 45 current 15, this source of current being common to but normally dissociated from the telephone lines and the link connectors. This source of current is preferably of such a nature that it may be retained in circuit 50 relation with connected telephone lines so as to supply the transmitters at the connected stations with direct current, though the invention is not to be limited to the functions which the common source of current 55 performs. Each time the contacts 5 and 6 of each of the hundred lines of a group are brought into engagement with their complemental contacts a circuit is established which is traceable from the 60 grounded battery 15, the winding of relay 13, the intermediate armature switch of relay 14 and its contact, the depressed contact 6, the contact complemental to the contact 6, both sides of the line having such contact 65 6, the contact 5 of this line, the contact

complemental to contact 5, the impedance 16, the right hand armature switch of relay 14 and its contact, to ground. When the telephone receivers are upon their switch hooks the line circuits are of too high resistance to cause the relays 13 to be energized owing to the resistance of the bells 2. When, however, a call has been initiated, the telephone bridge at the calling station joins the line sides through a path of sufficiently low resistance to permit sufficient flow of battery current through the relay 13 to cause this relay to be energized thereby to open the circuit of the motor magnet at the normal contact of the armature switch of the relay 13 to prevent further operation of this motor magnet whereby the contacts 5 and 6 are maintained depressed and in connection with their complemental contacts. The relay 13 is desirably of five thousand ohms resistance and the impedance device 16 is desirably of five thousand ohms resistance.

When the relay 13 is energized its armature switch engages its alternate contact to 90 establish a circuit traceable from the grounded battery 15, the left hand armature switch of relay 14 and its contact, the armature switch of relay 13 and its alternate contact, the winding of relay 17, the contact 6 95 pertaining to the calling line, the contact complemental to this contact, both sides of the calling line, the contact 5 of the calling line, the contact complemental to the contact 5, the impedance 16, the right hand armature switch of relay 14 and its contact, to ground. When relay 17 is energized a circuit is established traceable from the grounded battery 15, through the two middle contacts of an operator's switching 100 mechanism 18, the left hand armature switch of relay 17 and its alternate contact, the winding of relay 17, the contact 6 of the calling line, the contact complemental thereto, both sides of the calling line, the 110 contact 5 of the calling line and the contact complemental thereto, the relay 19, the right hand armature switch of relay 17 and one of its contacts, to ground, the circuit just traced constituting a holding circuit for the 115 relay 17. When the relay 17 is energized a holding circuit is established at its right hand armature switch for the relay 13, which holding circuit is traceable from the grounded battery 15, the winding of relay 120 13, the right hand armature switch of relay 17 and one of its contacts, to ground. A third circuit is established at the right hand armature switch of relay 17 which is traceable from the grounded battery 15, the motor magnet 20, the wiper 21 fixedly carried upon the shaft of a ratchet wheel 22, a waiting contact engaged by the wiper 21, the right hand armature switch of relay 17 and one of its contacts, to ground. The motor 125 120

magnet 20 is then energized to step the ratchet wheel 22 one or more tooth spaces to bring its wiper 21 into engagement with the waiting contact that is associated with another relay 17 which is not energized, the ratchet wheel 22 continuing in motion until this wiper 21 is engaged with such a waiting contact pertaining to an unenergized relay 17, circuit for the motor magnet 20 then being opened at the right hand armature switch of such deenergized relay 17. It is understood that each motor element 8-9 has a relay 17 individual thereto. When the relay 19 was energized it opened a circuit at its left hand armature switch for the relay 14, the circuit for this relay 14 having been previously established when the motor magnet 20 was operated to bring the wiper 21 into engagement with a waiting contact that was then associated with the relay 17 when this relay was unenergized. The circuit for the relay 14 is traceable from the grounded battery 15, the middle contacts of the operator's switching mechanism 18 (there being one switching mechanism 18 for each motor device 8-9) the left hand armature switch of relay 19, when deenergized, and its contact, the winding of relay 14, a wiper 23 fixed upon the shaft of the ratchet wheel 22 and the waiting contact individual to the relay 14, to ground. The master switching mechanism comprising the elements 20, 21, 22 and 23 is common to each group of ten motor devices 8-9 and its relatively fixed wipers 21 and 23 have ten pairs of waiting contacts, in the example under illustration, the ten waiting contacts of the wiper 21 each being individual to a distinct relay 17 and therefore each individual to a distinct motor 8-9 as each motor 8-9 has a relay 17 individual thereto, while the ten waiting contacts of the wiper 23 are each individual to a distinct relay 14 and therefore each individual to a distinct motor 8-9, as each motor 8-9 has a relay 14 individual thereto.

By the organization described it will be seen that as each motor 8-9 has become arrested, owing to the establishment of a low resistance telephone bridge at a calling line station, in order to maintain the line contacts 5, 6 in engagement with their complementary contacts, the magnet 17 individual to such motor 8-9 becomes energized so to enable the master switching mechanism 20-23 to energize the relay 14 individual to some other but then idle motor 8-9 to bring this other motor into constant operation, itself to be arrested when its roller 11 depresses a pair of contacts 5, 6, of a calling line to join it with the link connector at such newly operating motor, the employment of this link connector newly selected by the master selector switch being thus predetermined to the exclusion of its idle companion in the same group. When the calling subscriber (station 120) restores his telephone upon its switch hook circuit for relay 17 associated therewith is opened at the calling subscriber's switch hook whereupon the circuits for the relays 13 and 19 are opened at the right hand armature switch of said relay 17. When the wiper 23 again reaches the waiting contact individual to this particular relay 14 associated with the previously calling line 120, this relay 14 is energized so that the motor 8-9 is brought into operation whereby the roller 11 may pass over the contacts 5 until it engages a contact 5 pertaining to a new calling line, with results previously described.

When one motor 8-9 has been brought to rest in association with a calling line in the manner previously described a second or some other motor in the same group will bring its rollers 11 into temporary depressing engagement with a contact 5 in multiple with the contact 5 of said calling line, this temporary depressing engagement occurring during the sweep of the arm 10. This second or other motor will not be arrested when in engagement with the said multiply related contact 5 owing to the comparative resistance of the relays 17, 19 which are preferably of two hundred fifty ohms resistance each and the relay 13 and impedance 16 each preferably of five thousand ohms resistance, the battery 15 being preferably of fifty volts. With this arrangement sufficient current is diverted from the element 13 of the second or other motor through the relays 17 and 19 connected with the calling line to prevent the energization of relay 13 pertaining to such second or other motor whereby such other motor is not arrested with its roller 11 in continuing engagement with a contact 5 in multiple with the contact 5 that is being maintained depressed by the roller 11 of the first motor 8-9 that is associated with such calling line.

The link connector for joining the calling line with a called line includes a connecting plug 24 having tip and sleeve strands, though the invention is not to be limited to such a connecting terminal. A relay 25, preferably of two hundred fifty ohms resistance, is connected with the tip strand of the plug 24 there being a condenser 26 interposed between the terminals of the relays 19 and 25. When the plug 24 is inserted in the jack of a called line and the called subscriber has responded sufficient current is diverted from the relay 13 of an operating motor 8-9 to prevent such operating motor from becoming arrested with its roller 11 in continuing depressing engagement with the contact 5 of the called line whose station has responded. For reasons previously explained, an operating motor 8-9 will not become arrested in association with

a desired line that has been plugged into owing to the absence of the low resistance telephone bridge at the called station, this prior to the ringing of the bell at the desired station. A ringing key 27 serves to bridge a ringing generator 28 between the tip and sleeve strands of the plug 24 to operate the bell 2 at the desired station. When this key is depressed the nose 29 of the lower 5 armature of a relay 30 engages the notch 31 in the key shank so as to hold said key in its ringing position. The relay 30, which may be of twenty ohms resistance, is in series with the generator 28, the resistance 10 of the signal bell 2 cutting down the ringing current sufficiently to prevent the relay 30 from being energized while the bell 2 is in circuit. When the called subscriber responds the low resistance telephone bridge 15 at the called station will permit a sufficient increase in the flow of current from the generator 28 through the relay 30 to energize the relay 30 to attract its lower armature 20 to withdraw the armature nose from the notch 31 to permit the automatic restoration of the key 27 thereby to cut the generator 28 out of circuit. When the relay 30 is energized a circuit is established through the relay 32 which may be traced from the 25 grounded upper armature of relay 30 and its contact, the winding of relay 32, the right hand armature switch of relay 19 and its contact, the two middle contacts of the operator switch 18 to the grounded battery 15. 30 The top and bottom armature switches of relay 32 thereupon establish continuations of the tip and sleeve strands of the plug 24. The middle armature switch of the relay 32 establishes a locking circuit for itself traceable from the grounded contact of this middle armature switch, said armature switch, the winding of relay 32, thence to the battery 15 by way of the right hand armature switch of the energized relay 19. While the 35 ringing key 27 was depressed a circuit was established traceable from the grounded impedance coil 33 of, say, two hundred fifty ohms resistance, the two contacts of the lower spring of the ringing key 34 and a portion of this spring, the relay 35 of, say, 40 two hundred fifty ohms resistance, thence to the grounded battery 15 by way of the right hand armature switch of relay 19. Thus potential is placed upon the thimbles 45 of the multiple jacks in connection with the called line and also upon the contacts 6 of the called line. The potential placed upon the thimbles is furnished by a connection traceable from the grounded battery 50 55 60 65 15, the middle pair of contacts of the key 18, the right hand armature switch of the relay 19 and its contact, the relay 35, the ringing switch spring 34 and one of its contacts, the heel of the plug 24 engaging the jack of the busy line, thence to the other

thimbles of this line. It should be observed in passing that the spring 34 engages its contacts before the companion ringing spring engages its contacts when the plunger 27 is depressed.

When a desired line is tested the test circuit is continued from the thimble of the tested jack of the desired line through the tip of the testing plug 24, the upper armature switch of relay 32 and the contact normally engaged thereby, the upper spring of the testing operator's listening key 36 and the two contacts then engaged thereby, to the grounded connection provided for the operator's receiver. The potential upon the 80 thimbles of the calling lines is established for testing purposes by way of a connection traceable from the grounded battery 15, the winding of relay 13 associated with the calling line, the middle armature switch of relay 14, the contact complementary to the contact 6 of the calling line, the contact 6 of the calling line, thence to the thimbles of the calling line jacks.

To prevent any motor 8-9 from remaining in continuing engagement with a contact 5 of a line over which ringing current is being passed effective current from battery 15 is prevented from flowing through the coil 13 by a shunt established for the 95 battery current traceable from the grounded battery 15, the middle contact of the key 18, the right hand armature switch of the relay 19, the relay 35, the two contacts engaged by the ringing spring 34, the impedance 100 105 110 115 120 125 130 33, to ground. If the calling party restores his telephone before the called party responds, relay 35 will be deenergized owing to the breaking of the circuit thereof at the right hand armature switch of relay 19 whereupon circuit for relay 30 is established at the armature switch of relay 35 to withdraw the lower armature of relay 30 from engagement with the ringing key 27 thereby to remove the ringing generator 28 from circuit with the called line. The tip and sleeve strands leading to the plug 24 are, in this instance, extended to the contacts that are complementary to the contacts 5 and 6. Each answering end of a link having a connecting plug 24 is provided with one hundred sets of contacts, in the system specifically chosen for an example, that are complementary to the contacts 5, 6 so that each connecting plug 24 is adapted to be constituted an extension of any of the telephone lines in the group of one hundred. Thus the calling subscriber, in addition to causing the operations which have been described also, in the embodiment of the invention herein shown, automatically extends his telephone line into connection with an operator controlled terminal 24, though this invention is not to be thus restricted. When the answering end of a link connector has

thus become automatically connected with the calling line and the connecting end of the link connector has been manually connected with a called line by the operator, 5 the calling and called telephone lines are placed in connection and are in telephonic connection when the receivers at both stations are free of their switch hooks. When the subscribers restore their telephones upon 10 their switch hooks when through their conversation, the paths for current from the battery 15 through the telephone lines are broken owing to the breakage of the low resistance telephone bridges at the stations 15 whereby the relay 17 is deenergized to clear the line and link of battery, this relay remaining energized as long as either telephone is free of its switch hook. When the relay 17 is deenergized the relay 19 is deenergized and the relay 32 is also deenergized to restore its armature switches to normal, the calling and called lines being again separated at the top and bottom armature 20 switches of relay 32. By clearing the link 25 and lines of battery when both telephones of connected stations are restored to their switch hooks, the roller 11 may remain in depressing engagement with the contact 5 of the calling line and, owing to the then deenergized condition of the relay 32, the 30 plug 24 may remain in the jack of the called line, no battery being furnished to the particular link until the motor magnet 20 again brings its wiper 23 into connection with the 35 waiting contact individual to the relay 14 of this link so that another subscriber may employ this link for resuming his connection with the other subscriber until the relay 14 of this link has thus become connected 40 with the wiper 23 of the master switch. As a result the traffic in the system is not interfered with even though the broken link connectors remain in connection with lines which they previously joined. The relay 19 45 is within the control of the calling subscriber and the relay 25 is within the control of the called subscriber owing to the presence of the condenser 26. The right hand armature switches of these relays are 50 made to operate display devices so that these relays are constituted supervisory relays or signals. When the relay 19 is initially operated upon the initiation of a call by a calling subscriber its right hand armature 55 switch operates the signal device and the operator, in response to such signal, depresses her listening key 36 to bridge her telephone set between the sides of the link connector automatically selected by the calling subscriber to ascertain the number of 60 the line wanted, though it is to be understood that the invention is not to be limited to a system in which the signal device 19 is thus operated to attract the attention of 65 the operator.

Each link connector has an operator's key 18 provided with three pairs of contacts and a switch lever in one position separating the contacts of one pair and closing the contacts of another pair, and in another position 70 joining the contacts of the remaining pair. When the contacts of the middle pair of a key 18 are separated the relay 14 individual thereto has its circuit broken thereat. Each key 18 has a left hand pair of contacts 75 which, when the key is operated to separate the middle pair of contacts, establishes a circuit through the motor magnet 20 to prevent the motor magnet from being tied up with a link connector that is put out of 80 service by the operator. The ten link connectors pertaining to a group of ten motors 8-9 are desirably distributed among ten operators, each link connector having a motor individual thereto and each motor being 85 associated with the contacts 5, 6 of one hundred lines. Thus each operator has a motor 8-9 in each of ten groups of ten such motors and thus has access to one thousand lines. By this system the operators employed are in proportion to the traffic, the switches 18 at each unattended operator's position being thrown, as hitherto described, to prevent calls from being received at such unattended positions. 90 When the right hand contacts of any key 18 are engaged the operator may call a line and, upon depressing her key 36, may converse with the station she calls. The closure of the right hand contacts of the key 100 18 establishes a circuit for the relay 17 (by way of the operator's telephone set) to enable the operator to manipulate her ringing key 27 and secure connection with a line by means of the associate plug 24. The energization of the relay 17 thus effected by the operator prevents the associate link connector from being appropriated by a calling line. In addition to the other advantages 105 which have been recited the normal absence 110 of battery upon the telephone lines and link connectors is an important factor, as will be apparent without further comment. Condensers 13¹, 16¹ serve to receive discharges occurring when rollers 11 pass contacts of 115 telephone lines.

While I have herein shown the contacts 5, 6 as being individual to and permanently connected with the telephone lines, it is obvious that the invention is not to be restricted to such a characteristic in all of its embodiments. In the organization described the wheels 11 are in traveling relation to the contacts 5 and 6 and the invention discloses motor mechanism whereby the wheels 120 11 are themselves caused to travel while the contacts 5 and 6 and the contacts complementary to contacts 5 and 6 have stationary mountings. I do not limit myself to this mechanism for securing relative travel be- 125 130

tween the contacts 5 and 6 and the contact actuators 11.

While I have herein shown and particularly described the preferred embodiment of my invention, I do not wish to be limited to the precise details of construction and circuit arrangement shown as changes may readily be made without departing from the spirit of my invention, but

10 Having thus described my invention I claim as new and desire to secure by Letters Patent the following:—

15 1. A telephone exchange system including telephone lines extending from telephone stations to an exchange where these telephone lines are provided with circuit controlling contacts; contacts complementary to the foregoing contacts; motor devices for changing the relation of these contacts; master switches for bringing the motor devices into operation; and mechanism governed by station apparatus of calling lines for causing the operation of the motor devices to cease upon changing the relationship of the contacts of calling lines with their complementary contacts and for thereupon causing the operation of the master switch to bring another motor device into operation.

20 2. A telephone exchange system including telephone lines extending from telephone stations to an exchange; switching devices for extending the line circuits; motor devices for operating the switching devices; master switches for setting the motor devices into operation; and means governed by apparatus at stations of calling lines for causing the motor devices to cease operation upon operating the switching devices to extend calling line circuits and for thereupon operating the master switch to bring an idle motor device into operation.

25 3. A telephone exchange system including telephone lines extending from telephone stations to an exchange; link conductors for uniting lines in conversation; switching devices for joining link connectors with calling lines; motor devices for operating the switching devices; master switches for setting the motor devices into operation; and means governed by apparatus at stations of calling lines for causing the motor devices to cease operation upon operating the switching devices to extend calling lines into connection with link connectors and for thereupon operating the master switch to bring an idle motor device into operation.

40 4. A telephone exchange system including telephone lines extending from telephone stations to an exchange where these telephone lines are provided with circuit controlling contacts; contacts complementary to the foregoing contacts; motor devices for changing the relation of these contacts; master switches for bringing the motor devices into operation; mechanism governed

45 by station apparatus of calling lines for causing the operation of the motor devices to cease upon changing the relationship of the contacts of calling lines with their complementary contacts and for thereupon causing the operation of the master switch to bring another motor device into operation; and means whereby the master switch is prevented from bringing the motors that have been arrested by calling lines again into operation while the calling lines are in circuit with calling station telephones.

50 5. A telephone exchange system including telephone lines extending from telephone stations to an exchange; switching devices for extending the line circuits; motor devices for operating the switching devices; master switches for setting the motor devices into operation; means governed by apparatus at stations of calling lines for causing the motor devices to cease operation upon operating the switching devices to extend calling line circuits and for thereupon operating the master switch to bring an idle motor device into operation; and means whereby the master switch is prevented from bringing the motor devices that have been arrested by calling lines again into operation while the calling lines are in circuit with calling station telephones.

55 6. A telephone exchange system including telephone lines extending from telephone stations to an exchange; link connectors for uniting lines in conversation; switching devices for joining link connectors with calling lines; motor devices for operating the switching devices; master switches for setting the motor devices into operation; means governed by apparatus at stations of calling lines for causing the motor devices to cease operation upon operating the switching devices to extend calling lines into connection with link connectors and for thereupon operating the master switch to bring an idle motor device into operation; and means whereby the master switch is prevented from bringing the motor devices that have been arrested by calling lines again into operation while the calling lines are in circuit with calling station telephones.

60 7. A telephone exchange system including telephone lines extending from telephone stations to an exchange where these telephone lines are provided with circuit controlling contacts; contacts complementary to the foregoing contacts; motor devices for changing the relation of these contacts and common to a plurality of sets thereof; master switches for bringing the motor devices into operation; and mechanism governed by station apparatus of calling lines for causing the operation of the motor devices to cease upon changing the relationship of the contacts of calling lines with their complementary contacts and for thereupon causing

the operation of the master switch to bring another motor device into operation.

8. A telephone exchange system including telephone lines extending from telephone stations to an exchange; switching devices for extending the line circuits; motor devices for operating the switching devices and common to a plurality of such switching devices; master switches for setting the motor devices into operation; and means governed by apparatus at stations of calling lines for causing the motor devices to cease operation upon operating the switching devices to extend calling line circuits and for thereupon operating the master switch to bring an idle motor device into operation.

9. A telephone exchange system including telephone lines extending from telephone stations to an exchange; link connectors for uniting lines in conversation; switching devices for joining link connectors with calling lines; motor devices for operating the switching devices and common to a plurality of such switching devices; master switches for setting the motor devices into operation; and means governed by apparatus at stations of calling lines for causing the motor devices to cease operation upon operating the switching devices to extend calling lines into connection with link connectors and for thereupon operating the master switch to bring an idle motor device into operation.

10. A telephone exchange system including telephone lines extending from telephone stations to an exchange where these telephone lines are provided with circuit controlling contacts; contacts complementary to the foregoing contacts; motor devices for changing the relation of these contacts and common to a plurality of sets thereof; master switches for bringing the motor devices into operation; mechanism governed by station apparatus of calling lines for causing the operation of the master switch to bring another motor device into operation; and means whereby the master switch is prevented from bringing the motor devices that have been arrested by calling lines again into operation while the calling lines are in circuit with calling station telephones.

11. A telephone exchange system including telephone lines extending from telephone stations to an exchange; switching devices for extending the line circuits; motor devices for operating the switching devices and common to a plurality of such switching devices; master switches for setting the motor devices into operation; means governed by apparatus at stations of calling lines for causing the motor devices to cease

operation upon operating the switching devices to extend calling line circuits and for thereupon operating the master switch to bring an idle motor device into operation; and means whereby the master switch is prevented from bringing the motor devices that have been arrested by calling lines again into operation while the calling lines are in circuit with calling station telephones.

12. A telephone exchange system including telephone lines extending from telephone stations to an exchange; link connectors for uniting lines in conversation; switching devices for joining link connectors with calling lines; motor devices for operating the switching devices and common to a plurality of such switching devices; master switches for setting the motor devices into operation; means governed by apparatus at stations of calling lines for causing the motor devices to cease operation upon operating the switching devices to extend calling lines into connection with link connectors and for thereupon operating the master switch to bring an idle motor device into operation; and means whereby the master switch is prevented from bringing the motor devices that have been arrested by calling lines again into operation while the calling lines are in circuit with calling station telephones.

13. A telephone exchange system including telephone lines extending from telephone stations to an exchange; switching devices for extending the line circuits; motor devices for operating the switching devices; master switches for setting the motor devices into operation; and means governed by apparatus at stations of calling lines for causing the motor devices to cease operation upon operating the switching devices to extend calling line circuits and for thereupon operating the master switch to bring an idle motor device into operation, said means including relays for establishing the operating circuits for the motor devices, contacts whose circuit relations are governed by the master switches and which are individual to said relays for establishing the relay circuits to establish the operating circuit of the motor devices, and an operating circuit for said master switch for breaking the circuits of said relays and which operating circuit is established by calling line apparatus for this purpose whereby the motor devices are caused to cease their operation.

14. A telephone system having lines extending from stations to an exchange; line extensions, each complete line extension being divided into permanently serially related normally separated sections; line extending devices having line extending terminals; means for effecting relative movement between line terminals and line ex-

tending terminals to connect lines with line extensions and operating normally to effect engagement between line terminals and line extending terminals; and operator controlled electro-magnetic means for joining the sections of line extensions taken for use.

15. A telephone system having lines extending from stations to an exchange; calling line extensions, each complete line extending 10 tension being divided into permanently serially related normally separated sections; calling line extending devices having calling line extending terminals; means for effecting relative movement between line terminals and line extending terminals to con-

nect calling lines with calling line extensions and operating normally to effect engagement between line terminals and calling line extending terminals, and operator controlled electro-magnetic means for joining 20 the sections of the line extensions taken for use.

In witness whereof, I hereunto subscribe my name this thirty-first day of March, A. D. 1913.

ELMER R. CORWIN.

Witnesses:

G. L. CRAGG,
E. L. WHITE.
